OTHER PUBLICATIONS

Design U.S. Appl. No. 29/771,258, filed Feb. 22, 2021, entitled
"Utensil Handle", first named inventor: Marc Zemel.

Primary Examiner — Janice Patyk

Assistant Examiner — Kendra L Hebel

(74) Attorney, Agent, or Firm — Carter, DeLuca & Farrell
LLP

(57) **CLAIM**

The ornamental design for a utensil handle, as shown and
described.

DESCRIPTION

FIG. 1 is a front perspective view of a utensil handle shown
in a locked configuration, showing our new design;
FIG. 2 is a top plan view thereof;
FIG. 3 is a bottom plan view thereof;
FIG. 4 is a left side elevational view thereof;
FIG. 5 is a right side elevational view thereof;
FIG. 6 is a rear elevational view thereof;
FIG. 7 is a front elevational view thereof;
FIG. 8 is a front perspective view thereof, shown in an
unlocked condition;
FIG. 9 is a top plan view thereof;
FIG. 10 is a bottom plan view thereof;
FIG. 11 is a left side elevational view thereof;
FIG. 12 is a right side elevational view thereof;
FIG. 13 is a rear elevational view thereof;
FIG. 14 is a front elevational view thereof; and,
FIG. 15 is a front perspective view thereof, shown in a
folded condition.
The broken lines showing the scoop illustrate environmental
structure and forms no part of the claimed design.
